UNITED STATES PATENT OFFICE

130,336

DESIGN FOR A FACE PLATE FOR A COMBINATION ELEVATOR HALL LANTERN AND POSITION INDICATOR

Harry Emil Fritzam, Jamaica, and Morrison John Brounn, Forest Hills, N. Y., assignors to Otis Elevator Company, New York, N. Y., a corporation of New Jersey

Application August 2, 1941, Serial No. 102,671

Term of patent 14 years

To all whom it may concern:

Be it known that we, Harry Emil Fritzam, a citizen of the United States and a resident of Jamaica, county of Queens, State of New York, and Morrison John Brounn, a citizen of the United States and a resident of Forest Hills, county of Queens, State of New York, have invented a new, original, and ornamental Design for Face Plate for a Combination Elevator Hall Lantern and Position Indicator, of which the following is a specification, reference being had to

the accompanying drawing, forming part thereof.

The figure is a perspective view of a face plate for a combination elevator hall lantern and position indicator, showing our new design.

What is claimed is:

The ornamental design for a face plate for a combination elevator hall lantern and position indicator, substantially as shown.

HARRY EMIL FRITZAM.
MORRISON JOHN BROUNN.
